UNITED STATES PATENT OFFICE.

NORMAN B. WILDER, OF PROPHETSTOWN, ILLINOIS, ASSIGNOR OF ONE-HALF TO H. E. PADDOCK AND W. F. MILLIKEN, OF SAME PLACE.

BALING-PRESS.

SPECIFICATION forming part of Letters Patent No. 593,148, dated November 2, 1897.

Application filed March 26, 1897. Serial No. 629,409. (No model.)

To all whom it may concern:

Be it known that I, NORMAN B. WILDER, a citizen of the United States, residing at Prophetstown, in the county of Whiteside and State 5 of Illinois, have invented certain new and useful Improvements in Baling-Presses; and I do hereby declare the following to be a full, clear, and exact description of the invention, such as will enable others skilled in the art 10 to which it appertains to make and use the same.

This invention relates to certain improvements in baling-presses and powers therefor.

The object of the invention is to provide 15 certain improvements in rebounding-plunger baling-presses whereby a most durable, simple, powerful, and efficient baling-press will be provided, composed of a minimum number of parts for the purposes intended and 20 results to be attained.

A further object of the invention is to provide certain improvements in powers for rebounding-plunger baling-presses, which will be simple and durable in construction and 25 composed of a minimum number of parts.

The invention consists in certain novel 30 features in construction and in combinations and in arrangements of parts, as more fully and particularly pointed out and described

hereinafter.

Referring to the accompanying drawings, Figure 1 is a side elevation of the press provided at its frontend with the power to which a steam or other engine is coupled. Fig. 2 is 35 an end view thereof. Fig. 3 is a longitudinal central sectional view of the press of Figs. 1 and 2. Fig. 4 is a top plan view of the press of Fig. 1. Fig. 5 is a detail perspective view showing the bed-beams and various parts 40 which are coupled thereto detached and separated. Fig. 6 is a detail cross-sectional view taken through the front supporting-axle, showing the front ends of the bed-beams and the king-bolt and the manner of coupling the 45 lower end thereof to the axle. Fig. 7 is a detail top plan of the bed-beams, the frame and parts of the machine being removed on the section-line 77, Fig. 1. Fig. 8 is a detail perspective view of the sheave to which the 50 plunger-operating cable is attached, showing

the sheave-actuating trip rigid with the shaft of the sheave. Fig. 9 is a detail view, partly in section, of the joint in the presser-head-operating toggle. Fig. 10 is a detail diagrammatical view of the mechanism for controlling the trip-shaft and throwing the trip out of the path of the trip-operating projection. 55

The frame of the baling-press generally comprises four parallel bars *a*, arranged horizontally and a suitable distance apart to form 60 what might be termed a "rectangular" four-sided structure. These bars are connected by suitable cross-frames, while an intermediate portion of the frame is inclosed or otherwise suitably formed to constitute a baling-chamber *b* of any suitable or desirable structure, which in itself forms no part of my present invention. The baling-chamber terminates rearwardly in the open slideway 65 between the upper and lower bars of the frame, 70 where the division-boards (not here shown) can be introduced and the proper bale-ties inserted. The rear ends of the beams are united by the pressure-applying device *c*, of any suitable construction, forming no part of 75 my present invention, the completed bales being discharged, as usual, between the rear ends of the bars, the hay being compressed in the baling-chamber and forced therefrom along between the bars *a* in rear of the chamber, 80 where suitable pressure is applied thereto by drawing the ends of the bars toward each other by the pressure device *c*.

a are the retaining devices, of any suitable construction, extending through the side walls 85 of the baling-chamber to perform their well-known function in preventing retrograde movement of the hay after being compressed by the plunger hereinafter referred to.

The baling-chamber has the top feeding-opening *b'*, which can be provided with any suitable hopper or table for carrying the hay being passed into the feeding-opening, the sides or a portion of the hopper or table being shown in Fig. 4 and lettered *a²*. The 95 frame comprising the said longitudinal bars *a* extends forwardly a suitable distance in advance of the baling-chamber to carry the plunger-operating means, and the front end receives and is rigidly secured to an end head 100

or frame *d*, arranged vertically and provided with the depending lug or projection *d'* for the purpose hereinafter referred to.

e is the reciprocating presser or plunger head, preferably mounted and traveling on the antifriction-rolls *e'*, running on a suitable track or guideway formed by the floor of the baling-chamber and the frame in advance thereof. The plunger-head reciprocates through or partially through the baling-chamber, as usual, and is preferably recessed at its rear to receive the front end of the operating toggle or pitman pivotally joined to the head in said recess. The lower portion of the rear side of the head is provided with the two rearwardly-extending beveled or tapered projections *e*² which on the rebound of the plunger engage the curved cushioning-springs *f* to cushion or break the force of the rebound of the head. These springs are at their rear ends secured to the lower portion of the frame, with their curved free ends extending forwardly over the rigid stops *g* and beyond the same into the path traveled by said curved projections or surfaces *e*² of the head, so that when the head rebounds said curved surfaces engage said springs and force the same up against the tension thereof before said projections finally engage the rigid stops *g* formed in the frame, which positively limit the rearward throw of said head.

The presser-head-operating toggle or pitman comprises the long link *h*, at one end pivoted to the presser-head, as before described, and the shorter link *h'*, at one end pivoted to the forward end of the link *h* and at its opposite end pivoted to a rigid part of the frame of the machine at a point preferably below the horizontal plane in which the head reciprocates and in a manner hereinafter set forth. The shorter link *h'* is preferably composed of two parallel plates or bars arranged on opposite sides of the front end of the link *h* and confined thereto by a single pivot-pin *h*², which also passes through a recess *h*³, extending completely through the end of the link *h*, and in which a loose pulley *h*⁴ is arranged and mounted on the pivoted pin *h*², so that the pulley rotates in a vertical plane on the horizontal pivot-pin. The link *h* has the lateral bosses *h*⁵ rigid therewith, on which the ends of the bars forming link *h'* turn and are confined by the nut and head of the bolt *h*² and suitable washers.

i i are a pair of parallel horizontal strongly and usually similarly constructed bed-beams arranged parallel with and beneath the front portions of the lower frame-bars *a*, and usually, although not necessarily, extending from the front end of the frame rearwardly to a point beneath the front end of the baling-chamber. However I do not wish to limit myself to this precise relative length and exact arrangement of these bed-beams. These beams are strongly and rigidly secured to the under side of the frame-bars *a* at the front end by having their front ends *i* separated a suit-

able distance and arranged on opposite sides of the lug *d'* of the end head of the frame and secured thereto by the cross-pin or bolt *j*, passed through said ends of the bed-beams and the said lug. The rear ends of the said bed-beams have the transverse grooves or seats *i*² in their upper and lower faces, and the lower cross-head *k* extends transversely across the under sides of the rear ends of the said bed-beams and fits in the under cross-grooves thereof and has the raised ends at the outer sides of the beams forming the vertical shoulders *k'*, fitting the outer edges of the beams and thereby locking the beams together against separating movement. The upper cross-head *l* fits in the upper cross-grooves of the beams and extends transversely across said beams and at its ends rests on the extended ends of the under cross-head *k* and is provided with the upwardly-extending lugs or ears *l'*, engaging the sides of the frame of the press and thereby holding the two bed-beams against lateral play independent of the press-frame bars. The vertical tie-bolts *m* pass up through the projecting ends of the two cross-heads *k l* and along the outside of the baling-chamber and through a cross-head *n* on top of the baling-chamber, where the tie-bolts are provided with securing-nuts or other suitable and desirable locking means. The front ends of the bed-beams are thus rigidly secured to the front head of the frame, while the rear ends of the beams are also rigidly and strongly secured and confined to the under side of the frame-bars and also are secured together by the same means. These bed-beams are secured rigidly one against the other and are recessed at their inner faces to leave ample room and space for the free movement of the link *h'* of the toggle.

Just in advance of the cross-heads *k l* the inner faces of the two beams are recessed to form a space for the pulley *o*, which turns in a vertical plane on the cross-bolt *o'*, also assisting in securing the bed-beams together.

At the front end of the long central opening between the bed-beams and at their inner faces said beams have the longitudinally slotted or bifurcated portions *i*³ *i*³, which fit together or engage each other so that their longitudinal slots *i*⁴ coincide. These slots open through the rear ends of said portions into the central space between the beams and at their rear ends terminate in the shoulders *i*⁵, and the slotted portions *i*³ are separated from the bodies or main parts of the beams by the vertical spaces or recesses *i*⁶.

p is a bearing-block arranged in the front end of the space between the two bed-beams, with the two bosses *p' p'* extending laterally from the opposite side edges thereof to the inner faces of the two bed-beams. The lower ends of the two bars forming the link *h'* of the toggle have bearing-openings confined and turning on said bosses, and a bolt or pin *q* is passed transversely through the bed-

beams and through the bearing-block, passing centrally through said bosses. The bearing-block is provided with a forwardly-projecting shank p^2 , extending into the slots i^4 5 from the front end thereof and fitting snugly therein and at its rear end abutting against the shoulder i^5 at the inner end of the slot, while the block has a shoulder p^3 fitting and abutting against the outer ends of the slotted 10 portions i^3 . A bolt r is passed transversely through the bed-beams and through said shank of the bearing-block. It will thus be observed that the pitman or toggle for actuating the presser-head, and also the presser-head, can be easily removed from the machine without separating or taking apart the frame by simply removing the bolts q r and sliding the bearing-block p rearwardly into the central open space until its shank leaves the said 15 slotted portions i^3 , when the said block can be lifted from the open space between the bed-beams and the ends of the link h' can be removed therefrom. The operation of again placing the parts in position and loosely confining the ends of the toggle-link is as easily performed, as the bearing-block with the link ends on its journal-bosses has merely to be placed in proper position between the bed-beams with its shank in the slot formed by 20 25 30 the two slots i^4 of the two beams and the bolts q r placed in their proper positions. A most strong and rigid construction is thus provided for mounting the forward end of the toggle and of receiving the great forward thrust 35 40 45 thereof when the machine is in operation, as it will be seen that the forward thrust of the toggle on the bearing-block is against the rigid shoulder formed by the shoulders i^5 of the two bed-beams and against the front ends of the slotted portions i^3 , which shoulders are rigid with the bed-beams and so that the said strain is directly longitudinal of the bed-beams, although any down strain thereon is resisted by the front axle, hereinafter mentioned, and by the rear supporting and securing device of said beams, hereinbefore described.

s is a clevis or cable-securing device which has its lower end forked and passed down 50 through or into the recesses i^6 i^6 of the bed-beams and mounted on and secured by the bolt r , while the upper end of the clevis, above the bed-beams, has an eye to which the operating-cable is secured, as hereinafter described.

Just in advance of the slotted portions of the bed-beams and of the bearing-block said beams have a vertical recess therethrough in which a pulley t is located, turning freely on 60 the horizontal bolt or pin t' , passing through the bed-beams.

Just in rear of the lug d' of the end head of the frame the bed-beams come together and engage each other and are formed with the 65 transverse vertical semicylindrical grooves, which coincide to form the vertical bolt-hole

i^7 , extending from the top to the bottom of the beams to receive the vertical king-bolt u , having a suitable nut or other locking device at its upper end at the upper sides 70 of the bed-beams, and an annular shoulder u' , fitting the under sides of the bed-beams. At a distance below said shoulder said bolt has the enlarged circular flange or head u^2 , rounded or convexed on the upper surface 75 and flat on the under side, which rests on the upper edge of the front axle v of the press, while the lower end of the bolt beneath said flange is rounded (see u^3) and fits and rests in an upwardly-flaring rounded socket or 80 seat v' in the upper side of the axle. Plates v^2 v^2 are secured by suitable bolts at the front and rear edges of the axle with flanges or lips v^3 , projecting over the rounded upper face of the flange or head u^2 of the king-bolt and 85 beveled or curved at their under faces, so that the front axle is free to turn on the lower end of the bolt and its ends can swing vertically on the lower rounded end of the bolt as a fulcrum, which movement is permitted by 90 the rounded surfaces of the flange u^2 and the lips or flanges of the plates v^2 , while the axle has an extended bearing and base where the broad flange or head u^2 of the king-bolt rests thereon. 95

The front axle is provided with suitable supporting-wheels w , and a rear axle x is provided also, having supporting-wheels w mounted thereon.

The rear axle x is usually secured rigidly 100 to the frame beneath the front portion of the baling-chamber and has the tie-rods x' rigidly secured thereto at their rear ends and at their front ends rigidly secured to the vertical bolts m m , preferably at the lower ends 105 of said bolts just beneath the two cross-heads uniting the bed-beams, so that the front and rear axles are tied together and also to the frame and bed-beams, whereby the strain is generally distributed throughout the various 110 parts of the framework of the machine and a most strong and rigid structure is attained.

y is a strongly-constructed brace or leg extending in an inclined position downwardly and forwardly from the front end of the machine to engage the ground. The upper end of the leg is bifurcated to embrace the lug d' and fit between the front ends of the bed-beams, and said ends are perforated transversely to receive the pin securing the front 120 ends of the bed-beams to the said lug and which also serves to secure the said leg. A brace or tie rod y' is at the front end secured to an intermediate portion of the leg y and at its upper rear end secured to a rigid part of 125 the machine, such as one of the bed-beams. This leg, having its lower forwardly-inclined end engaging the ground, materially aids in holding the machine against forward movement, particularly when a plank, stake, or 130 other obstruction is placed in front of the lower end of the leg to prevent forward move-

ment of the leg and cause its front end to take into the ground and thus lock the machine in place.

The lower free end of the leg y has a slight vertical movement, and hence its tendency is to cause its front end to swing down and take into the ground under forward strain on the machine, so that any forward movement of the machine would cause the front end of the machine to rise or lift up on the said leg.

2 is a coiled retracting-spring for returning the presser when pressed rearwardly to its limit of rearward movement and at the completion of each compressing stroke. This spring can be arranged and secured in any desirable manner, although it is here shown as secured to the link h and to the frame or a rigid part thereof.

Referring to the power for actuating and releasing the presser-head-actuating toggle, 3 is a rotary drive-shaft arranged transversely of the frame and projecting at its ends beyond the same and usually mounted in suitable bearing or journal boxes mounted at the front portions of the upper sides of the top longitudinal frame-bars. At one end this shaft usually has the fly or balance wheel 3' rigid therewith and at the opposite end the driving-pulley 3" rigid therewith, on which the driving-belt 4 from a steam-engine or other actuating means is arranged to constantly rotate said drive-shaft in the same direction. A wheel or disk 3³ is also rigidly fixed on said drive-shaft 3 at the inner side of the driving-pulley, and this disk is provided with the eccentrically-arranged rigid stud 3⁴, projecting inwardly therefrom and having a loose roller mounted thereon. The front end head of the frame is provided with a central opening and with suitable journal-boxes 5 on opposite sides of said opening, in which the trip-shaft 6 is mounted transversely of the said head, with its ends projecting beyond the same. This trip-shaft is arranged parallel with and a distance below and forwardly from the rotary drive-shaft and has the sheave 7 rigidly mounted on the central portion thereof and located in the said opening in the frame-head. The presser-head-operating toggle-cable 8 is at one end secured to and adapted to wind on said sheave, and from thence passes down around the pulley t and rearwardly beneath the bed-beams to the pulley o , and from thence upwardly to the pulley h^4 at the joint in the toggle, and over the same and forwardly and downwardly to the clevis s , to which the end of the cable is securely fastened. It will be observed that the point where the cable is secured to the clevis s is a distance below the horizontal plane of the joint of the toggle at all points in the path of movement of said joint of the toggle, and that the pulley o is also below the plane of said joint of the toggle and rearwardly of the same, and that the length of the cable between said clevis and pulley o is stretched over the joint of the toggle. Hence when the cable is wound on the

sheave 7, the toggle being doubled up and the presser-head at its limit of forward movement, the cable draws down the joint of the toggle and straightens the same with great force and power, thereby driving in the presser-head to perform its pressing operation, as shown in Fig. 3.

The end of the trip-shaft adjacent to the wheel or disk 3³ of the rotary drive-shaft is provided with the trip 9, arranged in the circular path of the stud or projection 3⁴ on said disk. This trip is strongly constructed and is at its inner end rigidly secured to the trip-shaft and extends laterally or radially therefrom beside the disk 3³ and is of such length and so arranged in relation to the stud 3⁴ that when the presser-head rebounds and reaches its limit of forward movement the trip is at its operative limit of forward movement with its extremity just within the path of rotation of said projection, about as shown in the diagrammatical view Fig. 13. As the drive-shaft revolves the said projection 3⁴ engages the edge of the trip near the extremity thereof and forces the trip around ahead of the projection, the projection moving along toward the inner end of the trip, thereby moving the trip in a direction which rotates the trip-shaft and winds up the cable on the sheave of the trip-shaft and forces the presser-head into the baling-chamber in its compressing stroke. When the projection 3⁴ reaches its limit of inward movement on the edge of the trip, the presser-head has completed one-half of its inward or compressing stroke and the projection reaches its limit of inward movement on the trip as it passes around under or beside the end of the trip-shaft and as the trip enters the plane connecting or in which the drive-shaft and the trip-shaft are located. As the projection forces the trip beyond said plane the presser-head starts in on the second half of its compressing stroke, and the projection travels toward the outer end of the trip, and as the projection reaches the end, or nearly reaches the end, of the trip the presser-head reaches that part of the baling-chamber where it meets the greatest resistance from the compressed hay. Thus when the presser-head reaches the point of greatest resistance to its further rearward progress the projection 3⁴ is near the end of the trip, and hence exerting great force and leverage on the trip-shaft in rotating the same to wind the toggle-operating cable on the sheave. The projection 3⁴ hence reaches a point near the end of the trip and has its greatest leverage on the trip-shaft when the presser about reaches the limit of its compressing stroke. As the trip-actuating projection continues to move around it presses the trip inwardly and slips off the rounded end of the trip and passes around beyond the same after it has swung the trip around about two-thirds or two hundred and forty degrees of a complete circle. The trip and its shaft being thus released, the plunger at once rebounds under the action of the re-

tracting-spring 2 and the elasticity of the compressed hay, thereby drawing up the toggle-operating cable and unwinding the same from the sheave and rotating the trip to throw the 5 trip back again to its start position with its extremity in the path of the trip-operating projection in readiness to be engaged thereby and again swung around to repeat the compressing operation. A most rapid, simple, 10 and exceedingly powerful presser-head-operating power is thus provided for rebounding presser-heads which exerts the greatest power and leverage on the presser-head at the beginning and completion of its compressing 15 stroke.

The engaging edge or surface of the trip is preferably curved, with the intermediate concave depression terminating in the rounded-out or convexed surfaces toward the ends of 20 the trip, so that an extended bearing or engaging surface is provided for the circularly-moving trip-operating projection which extends the swing of the trip and stroke of the presser-head.

25 The power can be easily and quickly thrown out of gear, so that the driving-shaft 3 can continue to rotate without rotating the trip-shaft or presser-head, by simply rotating the trip-shaft after the presser-head has rebounded, and the trip is in its normal position at the starting-point to move the trip in toward the driving-shaft, so that its extremity passes in beneath the trip and out of the circular path of said projection. The projection is thus 35 free to travel completely around the trip without engaging the same. Various means can be provided to thus throw the trip out of gear and back to its operative position at the starting-point. As an example of several 40 constructions which can be provided for this purpose I show a cross-head 10, rigid on the end of the trip-shaft opposite the trip, having the upper and lower flexible connections 11 secured to the opposite ends thereof 45 and extending rearwardly along the exterior of the side of the machine to and secured to an upright lever 12 at opposite sides of the fulcrum-point 13 thereof. Other operating means can be employed instead of the lever, 50 which is usually fulcrumed at the side of the rear portion of the baling-chamber within convenient reach of the persons feeding the machine and applying the bale-ties. This lever is mounted to swing in a plane parallel 55 with the length of the machine and is provided with any suitable locking means, as a spring-pawl and toothed segment. Each connection 11 has a coiled retractive spring 14, interposed therein and forming a part of the 60 connection. The parts are so arranged that when the machine is running the springs 14 will be in their normal condition when the trip is in its normal position at the starting-point, as in Figs. 1 and 10, and hence the 65 springs yieldingly prevent the trip swinging inwardly beyond its starting-point on the rebound of the plunger and backward swing of

the trip. It should be noted that the cross-head 10 turns with the trip-shaft, so that during the compressing operation the lower connection 11 slackens while the upper connection tightens and expands the coil-spring therein, and on the release of the trip and rebound of the plunger the cross-head and connections assume their normal positions shown 75 in Fig. 10. The trip is thrown in and out of operative position, as described, by throwing the upper end of the lever 12 rearwardly and thereby tightening the upper connection 11 and turning the trip-shaft to rock the trip out 80 of the path of the trip-operating projection.

A feeding device can be provided to intermittently or periodically force the hay down through the feeding-opening into the baling-chamber in front of the presser-head and after 85 each rebound thereof. To accomplish this object a rock-shaft 15 is mounted transversely on the frame-bars *a* at a point between the power and the baling-chamber. This shaft has an arm 16 rigid therewith and extending 90 laterally therefrom and rearwardly over the machine with its rear end curved down and formed with an enlarged head or rake 17, which is normally located a distance above the feed-opening of the baling-chamber. An 95 operating-arm 18 is rigid with and extends forwardly from said rock-shaft, with the curved end arranged at such a point in the circular path of the trip-operating projection 3⁴ that the projection will move up beneath and engage said arm 18 and lift the same, and hence force the feeder rake or head 17 down into the baling-chamber just after the presser-head has in its rebound passed forwardly from beneath said opening. After the trip-operating 105 projection has operated the feeder to force and press down a sufficient quantity of hay in front of the presser-head the said projection slips past the curved end of said arm 18 and the feeder returns to its normal position, 110 with the rake-head 17 elevated and the arm 18 engaging and resting against a rigid stop 20. The feeder can be constructed in any suitable manner to normally maintain the elevated position of the rake-head, as by having 115 the arm 18 weighted or formed heavier than the opposite end carrying the rake-head. In this connection it should be noted that the presser-head of the machine carries, as usual, an apron, (not here shown,) which closes the 120 feeding-opening of the baling-chamber when the head is performing the compressing operation and which moves back to open the feeding-opening when the head rebounds. This apron can be of any ordinary and suitable construction, such as is well known to 125 those skilled in the art.

It is evident that various changes and modifications might be made in the forms, constructions, and arrangements of the parts described without departing from the spirit and scope of my invention. Hence I do not wish to limit my invention to the constructions specifically set forth herein, but consider my-

self entitled to all such changes and variations as fall within the spirit and scope of my invention.

Having thus fully described my invention, 5 what I claim as new, and desire to secure by Letters Patent of the United States, is—

1. In a baling-press, the combination of a frame, a baling-chamber, a reciprocating presser-head, bed-beams longitudinally secured to and beneath the frame, a presser-head-operating toggle, a bearing-block on which the outer end of the toggle is mounted, said block removably secured to and between the bed-beams so that the toggle and presser-head can be easily removed from the machine, and operating mechanism for the toggle, substantially as described.

2. The combination of a baling-press frame, a reciprocating presser-head, an operating- 20 toggle therefor, bed-beams secured together and to the under side of the frame, and having a longitudinally-slotted portion or seat therein, a bearing-block on which the outer end of the toggle is mounted to swing, said block removably sliding in said seat or slotted portion, means to removably lock the block therein, and toggle-operating mechanism, substantially as described.

3. In a baling-press, the combination of a 30 frame, a reciprocating rebounding presser-head and its operating mechanism, a track or way on which the head travels terminating in stops to limit the rebound of the head, springs extending beside the stops, the head 35 having curved surfaces to engage said springs to force them aside before the head engages the stops, substantially as described.

4. A baling-press, in combination with a press-operating cable, a cable swinging and 40 releasing mechanism on the press and comprising a trip-shaft by which the cable is wound and unwound and having a lateral trip-arm, a continuously-rotating driving-shaft having a projection moving in a circular path to engage the trip and rotate the trip-shaft and then release the trip, a cross-head on the trip-shaft, a hand-operated mechanism at a convenient point on the press, connections from opposite ends of the cross-head 45 to said hand-operated mechanism, each connection having an interposed spring, for the purposes stated.

5. In a baling-press, the combination of a baling-chamber, a frame extending forwardly 55 therefrom having an end head, a rebounding presser-head, an operating-toggle, an actuating-cable for the toggle, a winding-shaft horizontally mounted on said head and having a sheave to which said cable is attached, a trip-arm rigid with one end of said shaft extended beyond the end head, a continuously-rotating drive-shaft mounted on the frame in a plane above and in rear of said winding-shaft and having an end wheel beyond and beside 60 said trip-arm, and a projection rigid with and extending in front of said wheel and having an antifriction-roll thereon, said roll of the pro-

jection arranged to engage said trip-arm and swing it partially around and slip past the end thereof, as and for the purposes stated.

6. In a baling-press, the combination of a frame, a baling-chamber, a reciprocating presser-head and its operating mechanism, said head having a lower rearward extension, a bottom track on which the head travels terminating at the front in rigid stop-shoulders to engage said bottom extension of the head and limit its rebound, and cushioning devices arranged in the path of said extension at said shoulders and engaging said extension just before the same strikes the shoulders, substantially as described.

7. In a baling-press, the combination of a frame, a baling-chamber having a top opening, a presser-head and its operating mechanism, an operating power therefor mounted at the front end of the frame and comprising a rotary member having a projection moving in a circular path, and a feeder for forcing the material through said top opening of the baling-chamber, said feeder arranged above the baling-chamber and swinging at an intermediate point and having the forwardly-extending portion with a curved end arranged in the path of said projection, and operating substantially as described, the feeder disconnected from said projection and arranged to normally hold its feeding end elevated from the baling-chamber, substantially as described.

8. In a baling-press, the combination of a frame, a presser-head, an operating-toggle therefor, a toggle-operating cable, the pair of parallel bed-beams secured to and longitudinal of the frame, said beams having the central opening between them with the socket or slotted portion between the beams and at the front end of said opening and having the rearwardly-facing shoulders, the bearing-block between said beams and in said socket and having shoulders against said shoulders of the beams, the toggle having its front end between the beams and journaled to said block, substantially as described.

9. In a baling-press, the combination of a baling-chamber, the frame of the press extending forwardly of said chamber, a pair of parallel bed-beams arranged longitudinal of the frame of the press and beneath the same and extending from the baling-chamber to the front end of said frame, said bed-beams rigidly secured to the frame of the press at their front and rear ends and also secured together with the central space between them, their end portions being clamped directly together, a rebounding presser-head reciprocating in a plane above said bed-beams, an operating-toggle for said head with its front end mounted between said beams in rear of the front ends of said beams and at the front end of said space between the beams, and an operating-cable connected to the front portions of said beams in advance of the front end of the toggle and passing up over the joint of

the toggle and downwardly and rearwardly for connection with a power, substantially as described.

10. In a baling-press, the combination of a baling-chamber, the press-frame extending forwardly of said chamber, a pair of parallel bed-beams arranged longitudinally beneath the front portion of said frame, said beams at their front ends secured to the front end of the press-frame, the front supporting-axle beneath the front ends of said bed-beams, a clamp securing the rear ends of said bed-beams together and to the press-frame, the rear axle beneath the press-frame, tie-rods extending from the rear axle and coupled to said bed-beams, a rebounding presser-head, an operating-toggle therefor mounted to and between said bed-beams, and an actuating-cable for the toggle, substantially as described.

15. In a baling-press, the combination of a baling-press frame, a baling-chamber, a reciprocating presser-head, a part rigid with the frame having a seat or recess terminating in rearwardly-facing rigid shoulders, a bearing-block in said seat or recess abutting forwardly against said shoulders, a presser-head-operating toggle at its lower forward end mounted on said bearing-block so that the forward thrust of the toggle on said block is resisted by said rigid shoulders, and toggle-operating means, substantially as described.

20. In a baling-press, the combination of a frame, a baling-chamber, a reciprocating presser-head, a member rigid with the frame and having the projecting side journal-bosses, a presser-head-operating toggle comprising the link pivoted to the head and at the opposite end having the projecting side journal-bosses, the other link of the toggle made up of the two plates having the end bearings on said bosses, respectively, means confining the ends of said plates loosely on said bosses, and toggle-actuating means, substantially as described.

25. In a baling-press, the combination of a frame, a baling-chamber carried thereby, a reciprocating presser-head, a pair of parallel bed-beams arranged longitudinal of the frame and at their front ends secured to the front end of said frame and at their rear ends secured to the frame at the front portion of the baling-chamber, bolts passing transversely through said bed-beams and securing them together at their end portions, said beams having an open space between their intermediate portions, the head-operating toggle joined to said beams in rear of their front ends, and toggle-actuating means, substantially as described.

30. In a baling-press, the combination of a baling-chamber, the press-frame extending in advance of said chamber and provided with the vertical front-end head rigid therewith, a pair of bed-beams arranged longitudinal of and beneath said press-frame and at their front ends arranged on opposite sides of and rigidly secured to the lower end of said front-

end head, a clamp embracing the rear portions of said bed-beams and locking them together and secured to the press-frame at the baling-chamber, a reciprocating presser-head, an operating-toggle therefor at its front end mounted between said bed-beams in rear of their front ends, and a toggle-actuating cable secured to the bed-beams, substantially as described.

35. In a baling-press, the combination of a baling-chamber, the press-frame extending forwardly from the baling-chamber, the pair of parallel bed-beams at the under side and longitudinal of the press-frame and rigidly secured thereto, said beams secured together with their end portions against each other and with the open space between their intermediate portions, a clevis secured to said beams in advance of said space, a bearing-block secured between said beams at the front end of said opening, a pulley between the rear portions of the beams, a reciprocating presser-head, an operating-toggle therefor having a pulley in its joint and having its outer end mounted on said block, an actuating-cable secured to said clevis and passing upwardly over said pulley in the joint of the toggle and downwardly and rearwardly between said beams and over the pulley between the same, substantially as described.

40. In a baling-press, the combination of a baling-chamber, a press-frame extending in advance thereof, a pair of parallel bed-beams secured to the under side of the frame and together and having the open space between their intermediate portions, a bearing-block in said open space and secured between the bed-beams and having the projecting lateral journal-bosses on its opposite sides, a reciprocating presser-head, an operating-toggle therefor having its front-end link composed of two parallel plates having bearing-openings loosely receiving said bosses so that the lower ends of said plates are confined between the inner sides of the bed-beams and the sides of the bearing-block to turn on said bosses, and toggle-actuating means, substantially as described.

45. In a baling-press, the combination of a baling-chamber, the press-frame extending forwardly from the baling-chamber and provided with the vertical front-end head, the pair of parallel bed-beams extending longitudinal of and beneath the front portion of the press-frame and secured together and to the press-frame, a bolt clamping the front ends of said beams together and to and on opposite sides of the lower portion of said front-end head, a leg extending downwardly and forwardly from the front end of the press to the ground and having its upper end mounted on said bolt and arranged between the front ends of the bed-beams and said front-end head, a reciprocating presser-head, and actuating means therefor mounted on the bed-beams, substantially as described.

50. In a baling-press, the combination of a

baling-chamber, a press-frame extending forwardly therefrom and having a rear wheeled axle, a pair of parallel bed-beams arranged longitudinal of and beneath said frame and rigidly secured thereto and together, the front axle beneath the front ends of said bed-beams, the king-bolt arranged and secured between the front ends of said beams and extending below the same and loosely resting in the front axle and having the head above the same, means loosely confining the axle to said bolt, and a presser-head and its actuating means, substantially as described.

19. In a baling-press, the combination of the press-frame having a rear axle and wheels, bed-beams longitudinally beneath the front portion of the frame, a king-bolt secured therein and extending below the same and having the rounded lower end with an enlarged annular head above the said end with a rounded upper surface, the front axle having a socket in which said end loosely rests with said head on the axle, and plates secured to the axle and extending over the rounded upper surface of said head, substantially as described.

20. In a baling-press, the combination of a baling-chamber, a press-frame extending forwardly therefrom, the parallel bed-beams secured longitudinally of and beneath the front portion of said frame with the open space between their intermediate portions, the reciprocating presser-head, the operating-toggle thereof having its front end mounted between said bed-beams at the front end of said space between the same and in a horizontal plane below the path of travel of the presser-head, the actuating-cable at its front end secured to said bed-beams in advance of the front end of the toggle and from thence passing up over the joint of the toggle and then rearwardly and downwardly and down through the rear portions of the bed-beams at a point in rear of the limit of rearward movement of the joint of the toggle, a pulley at the rear portions of the bed-beams around which the cable passes, and a cable winding and releasing mechanism, substantially as described.

21. In a baling-press, the combination of a baling-chamber, the press-frame extending forwardly in advance of said chamber, a horizontal winding and releasing shaft mounted at the front end of said frame, a horizontal driving-shaft also mounted on the front end of said frame and actuating said winding-shaft, the reciprocating presser-head, the operating-toggle at its front end pivoted in rear of the front end of the frame in a plane below the path of the presser-head, an actuating cable secured in advance of the front end of the toggle and passing up over the joint of the toggle and downwardly and rearwardly therefrom, a pulley in rear of the limit of rearward movement of the joint of the toggle around which said cable passes and from which it passes forwardly beneath the frame,

a pulley at the front portion of the frame around which said cable passes up to the winding-shaft, substantially as described.

22. In a baling-press, the combination of a baling-chamber, a press-frame extending forwardly from the baling-chamber, a rebounding presser-head, an operating-toggle therefor comprising a long link joined to the head and a short link journaled at its front end in rear of the front end of the frame and in a plane below the horizontal path of movement of the head, the toggle-actuating cable at its front end secured at a point in front of and above the plane of the front end of the toggle and extending upwardly and loosely around the toggle at its joint and from thence rearwardly and downwardly to a point below and in rear of the limit of rearward movement of the joint of the toggle, a pulley at said point around which said cable passes, and cable winding and releasing mechanism to which the cable extends, substantially as described.

23. In a baling-press, the combination of a baling-chamber, a press-frame provided with a rear axle and extending forwardly from the baling-chamber and provided with a front-end head, paralleled bed-beams arranged at the under side of said frame from the baling-chamber to said front-end head, a clamp securing the rear ends of said beams together and to the press-frame at the front end of the baling-chamber, the front ends of the beams secured together and to said front-end head, the front axle beneath the front ends of said beams, a king-bolt secured to the front ends of the beams and on which the front axle is mounted, the rear axle tied to the rear portions of the bed-beams, a reciprocating presser-head, an operating-toggle connected to the bed-beams, and an actuating-cable therefor secured to the bed-beams so that the end thrust of the toggle is received by and longitudinal of said beams, substantially as described.

24. In a baling-press, the combination of a baling-chamber, a press-frame extending forwardly therefrom, a rebounding presser-head, an operating-toggle therefor, the toggle-actuating cable, a cable winding and releasing shaft horizontally mounted at the front end of the frame and having a sheave on which the cable is wound and at one end a laterally extending trip-arm rigid with the shaft, a continuously-rotating drive-shaft mounted horizontally at the front portion of the frame and provided with a wheel rigid therewith and provided with a projection moving in a fixed circular path and arranged to engage the end portion of said trip-arm and swing said arm around and move toward its inner end and then move toward its outer end and slip past the same and permit release of the winding-shaft and rebound of the plunger, substantially as described.

25. A frame, and an actuating-cable, in combination with a cable winding and releasing

shaft, to which said cable is secured, provided with a rigid lateral trip-arm, a drive-shaft arranged to revolve continuously in one direction and provided with a projection eccentric to the drive-shaft and moving in a fixed circular path, said trip-arm so arranged in relation to said projection that the projection when moving around first engages said arm near its outer end and swings the same around as the projection travels thereon toward its inner end and then travels toward its outer end and slips past the same and permits unwinding of the winding-shaft and return of the trip-arm, and whereby the greatest force is exerted on the winding-shaft at the beginning and ending of the stroke when the projection is in engagement with the outer end portion of the arm, substantially as described.

26. In combination, a rebounding presser-head, its operating-toggle, the toggle-actuating cable, a frame, a cable-winding shaft to which said cable is secured having a laterally-extending trip-arm rigid with one end thereof, a continuously-rotating drive-shaft parallel with and adjacent to the winding-shaft and provided with a wheel rigid with one end, and at the outer side of said trip-arm and so that the axis of the winding-shaft is within the circle of the circumference of said wheel, said wheel having a projection extending inwardly from a point near its circumference to engage said arm and swing the same so that its free end moves around from a point on one side of the drive-shaft to a point approximately diametrically opposite where the projection slips past the end of said arm and releases the same, substantially as described.

27. The combination of a frame, a driving-shaft arranged to rotate continuously in one direction and provided with a projection eccentric to the axis of the shaft and moving in a fixed circular path, a winding and releasing shaft arranged parallel with and adjacent to said driving-shaft so that the axis of the winding-shaft is arranged within the

circle in which said projection moves, and a trip-arm rigid with and extending laterally from the winding-shaft and arranged so that the end of said arm normally extends into the path of said projection and can be swung inwardly out of said path and toward the driving-shaft to throw the winding-shaft out of gear with the driving-shaft, and so that at its limit of winding swing said arm swings inwardly toward the driving-shaft and out of the path of said projection permitting the projection to slip past the end of the arm and the arm to return to its said normal position to be again engaged by the projection, substantially as described.

28. In combination, a frame, a driving-shaft having a projection eccentric to the axis of the shaft and moving in a fixed circular path, an actuating-cable, a cable winding and releasing shaft to which said cable is secured and by which it is wound to apply the power, means to unwind the cable from said shaft, the axis of said winding-shaft extending within the circle of said path of the projection, a trip-arm rigid with said winding-shaft and extending laterally therefrom so as to swing within the path of said projection, said trip-arm being so arranged in relation to said projection that at its limit of winding stroke it moves in toward the driving-shaft and out of the path of said projection to permit the projection slipping past the end of and releasing the trip-arm which then swings back with its free end in the path of said projection, and a yielding or spring device normally holding the end of the trip-arm in the path of said projection at its limit of releasing or unwinding movement, substantially as described.

In testimony whereof I affix my signature in presence of two witnesses.

NORMAN B. WILDER.
